UNITED STATES PATENT OFFICE

EDWIN SYKES, OF HUDDERSFIELD, ENGLAND.

YARN-TENSION DEVICE.

1,014,980.

Specification of Letters Patent. Patented Jan. 16, 1912.

Application filed March 13, 1911. Serial No. 614,010.

To all whom it may concern:

Be it known that I, EDWIN SYKES, a subject of King George V of Great Britain, residing at Huddersfield, in the county of 5 York, England, have invented certain new and useful Improvements in Yarn-Tension Devices, of which the following is a specification.

My invention relates to means for putting 10 tension on to yarn such as are employed in winding and similar machines in which yarn is dealt with, and my object is to provide an improved device for the purpose.

According to my invention, the yarn is 15 caused to pass around two series or sets of pins or studs, one set secured to a disk having segmental slots therein and capable of rotary movement within the limits of the slots on a fixed stud, and the other set or 20 series secured to a fixed disk and extending through the slots in the movable disk, the periphery of which is suitably weighted at one side. The yarn or thread is passed alternately around the two sets of pins in a 25 sinuous course, and the action of the weight on the periphery of the movable disk tends to partly rotate same in one direction to carry the pins thereon away from the pins on the stationary disk and the extent of 30 movement of the movable disk under the gravity action of the weight gives the necessary tension to the yarn throughout the winding or like operation.

In the accompanying drawing:—Figure 1 35 is a front elevation of a tension device embodying my improvements, and Fig. 2 is an edge or side view thereof.

Referring to the drawing, 1 represents a 40 fixed disk having a series of pins 2 projecting from the face thereof.

3 represents a movable disk, loosely pivoted at 4 concentrically with and in front of the disk 1 and having a series of segmental slots 5 through which the pins 2 on the fixed 45 disk project. Intermediate the slots 5 on the movable disk are a series of pins 6 which alternate with the series of pins 2. An adjustable weight 7 is connected in any suitable manner, and in the instance shown by a 50 hooked wire 7' to the periphery of the movable disk 3, the tendency of the weight being to rotate the movable disk within the limit of the segmental slots 5 in a direction contrary to the arrow A, Fig. 1.

55 The yarn 8, to which tension is to be ap-

plied, is passed alternately around the pins 2 and 6 taking a sinuous course, as shown, the tension being obtained by the pull on the yarn holding up the movable disk in the direction of the arrow A against the gravity 60 action of the weight which is tending to rotate the said disk in the opposite direction. The fixed disk is provided on opposite sides of its center with suitable guide eyes 9 to 65 guide the yarn and maintain it in its engagement with the pins. Means such as the handle 10 may be provided on the movable disk to rotate same to set the pins 6 apart from the stationary pins 2 to enable the yarn to 70 be passed between same without the necessity of threading the yarn around the pins, the release of the disk causing the yarn to be engaged by the pins in the manner shown. If desired, instead of employing weights as above set forth the fixed and movable disks 75 might be connected by a spring whose tension is adjustable, the pull on the yarn tending to hold up the movable disk against the pull of the spring.

The tension device constructed as above 80 set forth may be applied in any machines in which it is necessary to put tension on to a yarn or thread.

Having thus described my invention, what I claim as new and desire to secure by Letters Patent is:—

In a yarn tension device, the combination, 90 with a stationary disk, guide eyes projecting from the said disk at opposite sides of its center, and two rows of pins arranged radially between the guide eyes in line with each other and projecting from the face of the disk; of a movable disk pivoted concentric with the stationary disk and provided with curved slots which clear the said pins 95 and which limit the motion of the movable disk by contact with the said pins, two rows of pins projecting from the movable disk between its slots, and means for turning the movable disk automatically in one direction, 100 the yarn being passed from one guide eye to the other across the center of the disks and in a sinuous course between the pins.

In testimony whereof I affix my signature in the presence of two witnesses.

EDWIN SYKES.
